(57) **CLAIM**

The ornamental design for a wheel center cap as shown and described.

DESCRIPTION

FIG. 1 is a perspective view of a wheel center cap, showing my new design;

FIG. 2 is a front elevation view thereof;

FIG. 3 is an exploded view of FIG. 1;

FIG. 4 is a perspective view of a second embodiment of a wheel center cap;

FIG. 5 is a front elevation view thereof;

FIG. 6 is an exploded view of FIG. 4.

FIG. 7 is a perspective view of a third embodiment of a wheel center cap;

FIG. 8 is a front elevation view thereof; and,

FIG. 9 is an exploded view of FIG. 7.

The broken lines shown in the drawings are for the purpose of illustrating portions of the wheel center cap that form no part of the claimed design.

1 Claim, 9 Drawing Sheets
